Primary Examiner — Cynthia Ramirez(74) *Attorney, Agent, or Firm* — Simpson & Simpson, PLLC(57) **CLAIM**

The ornamental design for a step trash can, as shown and described.

DESCRIPTION

FIG. 1 is a front perspective view of the present invention step trash can;

FIG. 2 is a rear bottom perspective view of the invention;

FIG. 3 is a top plan view of the invention;

FIG. 4 is a bottom plan view of the invention;

FIG. 5 is a left side elevational view of the invention;

FIG. 6 is a right side elevational view of the invention;

FIG. 7 is a front elevational view of the invention; and,

FIG. 8 is a rear elevational view of the invention.

1 Claim, 5 Drawing Sheets*FIG. 1*
